G. R. WESTCOTT.
WAVE MOTOR.
APPLICATION FILED MAY 21, 1917.

1,259,179.

Patented Mar. 12, 1918.

UNITED STATES PATENT OFFICE.

GLEN R. WESTCOTT, OF LOS ANGELES, CALIFORNIA.

WAVE-MOTOR.

1,259,179.

Specification of Letters Patent. Patented Mar. 12, 1918.

Application filed May 21, 1917. Serial No. 170,032.

To all whom it may concern:

Be it known that I, GLEN R. WESTCOTT, a citizen of the United States, residing at Los Angeles, in the county of Los Angeles and State of California, have invented new and useful Improvements in Wave-Motors, of which the following is a specification.

This invention relates to a wave motor.

It is the principal object of this invention to provide a motor adapted to receive its impulse of movement from the force delivered by waves striking its vanes.

Another object of this invention is to provide a propeller for a wave motor which may be buoyantly supported upon the waves of the water and may be there rotated by the movement of the waves.

Another object of this invention is to provide a simple transmission mechanism through which the power developed may be delivered to driven machines and which is also adapted to be used to raise the propeller from the water under its own power.

It is a further object of this invention to provide a wave motor which is formed of a few inexpensive parts not liable to require repair and which will operate in a simple manner.

Other objects will appear hereinafter.

The invention is illustrated, by way of example, in the accompanying drawings in which:

Fig. 1 is a view in side elevation illustrating the wave motor with parts broken away for the sake of convenience.

Fig. 2 is a fragmentary view in section and elevation illustrating the manner in which the vanes are supported upon the propeller spider.

Fig. 3 is a view in plan illustrating a portion of the propeller spider.

Fig. 4 is a view in vertical section as seen on the line 4—4 of Fig. 1 and particularly illustrates the co-relation of the transmission gears with the driving shaft.

Referring more particularly to the drawings, 10 and 11 indicate rows of posts vertically positioned and suitably secured in the bed of the ocean. As here shown these posts are connected by the sub-frame 12 adjacent their lower ends. The upper ends of the posts are provided as supports for a platform 13 completing the motor frame. Positioned upon the upper face of the sub-frame 12 and disposed in the center thereof is a bearing 14. This bearing is provided to re-

ceive the lower round end 15 of a squared driving shaft 16 which extends vertically through the platform 13 and a bearing 17 therein. Slidably mounted upon the squared shaft 16 is a cylindrical float 18 preferably made of metal and adapted to buoyantly support a propeller spider 19. The spider is formed with a series of radial arms 20 extending outwardly from the hub and at equal angles to each other. The under face of each of these arms is fitted with a series of eye bolts 21 which are in turn engaged by rings 22. These rings are fitted upon the upper edge of propeller blades 23 and permit these blades to hang downwardly. Angle stops 24 are secured around the lower periphery of the float 18 and prevent the blades 23 from swinging away from the waves and cause them to resist the force of the waves in a manner to rotate the propeller. As the bearing through the propeller is square and is mounted upon a squared shaft the force of the water against the blades, as they are locked by the stops 24, will cause the shaft 16 to rotate.

The rotation of the shaft 16 imparts motion to a beveled gear 25 through which the shaft may slide. This gear is the main driving gear and is in constant mesh with the driven pinion 26 which is forced to the end of a transmission shaft 27. The shaft 27 is here shown as rotatably secured in a horizontal position within bearings 28 and 29. The opposite end of the shaft is fitted with a pulley 30, or other means for imparting the motion of the shaft to other mechanisms.

In order that the propeller will not require manual operation to raise and lower it from the surface of the water, a windlass 31 is provided. This windlass has a frame 32 which is secured to the upper end of the square driving shaft 16 and there supports a winding drum 33. A cable 34 is adapted to be wound upon this drum by means of a winding gear 35, in constant mesh with an idler gear 36. The winding gear is fastened upon the end of the drum shaft, the opposite end of this shaft being provided with a ratchet 37 engaged by a pawl 38 to prevent unwinding of the cable. The bevel gear 36 is free to rotate upon its mounting, which in the present case is around the driving shaft 16. In order that the cable may be led directly downward to the gear spider, an opening 39 is formed through the windlass frame and lengthwise

- 2
- of the shaft. This opening leads outwardly through the sides of the shaft just below the bearing 17. The lower end of this cable is fastened by an eye bolt 41 to the spider. 5 In this manner when the cable is wound upon the drum the spider will be lifted by the eye bolt 41 and raised from the water. It is to be noted further that rotation of the spider may continue during the raising 10 operation without tangling the cable, or causing it to be wrapped around the driving shaft. The mechanically operating means for rotating the windlass consists of a bevel clutch gear 42 which is mounted upon a sliding shaft 43. This shaft is supported within a frame 44 and may be shifted by a shifting lever 45. The lever 45 is formed with a yoke adapted to engage a shifting collar 46 which is secured 15 to the shaft. When the shifting lever 45 is swung in the direction of the arrow —a— the clutch gear 42 will be thrown into mesh simultaneously with the bevel gears 25 and 36 which have bevel faces opposite each 20 other. This will lock the driving gear 25 to the clutch gear 42 and impart motion to the gear 36 with which the winding gear 35 is in mesh. It will be observed that by this arrangement the windlass may continue 25 to rotate upon the shaft and the cable wound up as the propeller continues to rotate.
- In operation, the propeller, including the spider, blades and float, are lowered into the water. The float is of a size to buoyantly support the spider and permit the blades to lie substantially in the horizontal path of travel of the waves. As the waves strike the blades they will be swung downwardly until they encounter the stops 24 and will then cause the rotation of the float and the squared shaft 16, upon which the float is mounted. This rotation will impart motion to the driving gear 25 and will, in 30 turn, drive the gear 26 and the shaft 27. In case the sea becomes exceptionally rough and it is thought advisable to discontinue operations of the motor, the propeller may be raised from the water by shifting the 35 clutch gear 42 into mesh with the driving gear 25 and the bevel gear 36. This will cause the windlass to be rotated by the gear 35 and will wind the cable 34. As the cable is wound up, the propeller will, of course, be elevated and brought clear of the water. 40
- It will thus be seen that the wave motor here disclosed is simple in its construction, not liable to get out of order, and may be inexpensively made. 45
- While I have shown the preferred construction of my wave motor as known to me, it will be understood that various changes in the combination, construction and arrangement of parts may be made by those skilled in the art without departing from the spirit of my invention. 50
- I claim:
1. A wave motor comprising a frame, a shaft rotatably mounted vertically on the frame, a float slidably and nonrotatably mounted on the shaft, a propeller spider fixed upon the float, a series of hinged propeller blades depending from the spider radially to the shaft and free to swing one way, and stops to hold the blades from swinging the other way beyond a vertical plane. 55
  2. A wave motor, comprising a frame, a central vertical shaft rotatably secured by said frame, a propeller adapted to rotate with said shaft, means for buoyantly supporting said propeller upon the waves of a body of water, a transmission operated by the action of the water against the propeller, and means whereby said propeller may be raised from the water under its own power of rotation. 60
  3. A wave motor, comprising a frame, a vertical shaft mounted thereupon, a buoyant drum slidably positioned upon the shaft and adapted to rotate therewith, a propeller spider secured at the top of said buoyant drum and having arms extending radially therefrom, a series of hinged propeller blades vertically hung from said spider arms, means whereby the force of waves against the blades will cause the drum and shaft to rotate, and means whereby rotation of said shaft may be used to cause the propeller to be raised from the water. 65
- In testimony whereof I have signed my name to this specification.
- GLEN R. WESTCOTT.
